Inventor

By Cadhow & Co.

UNITED STATES PATENT OFFICE.

CAMERON ARTHUR KIDD, OF ANSTED, WEST VIRGINIA

HEATING DEVICE.

Application filed May 6, 1925. Serial No. 28,454.

To all whom it may concern:

Be it known that I, CAMERON A. KIDD, a citizen of the United States, residing at Ansted, in the county of Fayette and State 5 of West Virginia, have invented a new and useful Heating Device, of which the following is a specification.

This invention aims to provide a simple means whereby a single fire may be used 10 either as a grate fire in one room on one side of a partition, or be used to heat a drum in another room, on the other side of the partition, at the will of an operator.

It is within the province of the disclosure 15 to improve generally and to enhance the utility of devices of that sort to which the invention appertains.

With the above and other objects in view which will appear as the description proceeds, the invention resides in the combination and arrangement of parts and in the details of construction, hereinafter described and claimed, it being understood that changes in the precise embodiment of the invention herein disclosed may be made within 20 the scope of what is claimed, without departing from the spirit of the invention.

In the accompanying drawings:—

Figure 1 shows in elevation, a device constructed in accordance with the invention; Figure 2 is a vertical section wherein parts appear in elevation; Figure 3 is a horizontal section taken about on the line 3—3 of Figure 2.

The numeral 1 marks a partition in a building. The partition 1 has a vertical flue 2. The flue 2 forms walls 6 and 7 in the partition. There is a horizontal transverse opening 3 in the partition 1 at the floor 33 of the building. The wall 6 is broadened at its lower end, as shown at 4, to form a reduced throat 5 at the lower end of the flue 2. The wall 6 is supported on cross bars 8 and 9 mounted at their ends in the partition 1 at the sides of the opening 3. The wall 7 is supported on a cross bar 10, similarly mounted. The wall 7 has a small opening 11. The opening 11 is located immediately above the cross bar 10. The numeral 12 marks a drum which is curved transversely to form a front 14 and sides 15. The drum includes a top 16 having outlet perforations 17. The drum 12 is mounted in the opening 3 and projects outwardly beyond the partition 1, into one room of the building, as clearly indicated in Figure 2, the

perforations 17 in the top 16 of the drum 12 communicating with that room. The back of the drum 12 is in the form of a plate 18. The ends of the plate 18 are mounted in the partition 1 at the sides of the opening 3. The back plate 18 has a horizontal top flange 19. The flange 19 extends beneath the cross bar 9 and is secured to the cross bar 9, as shown at 20. The top 16 of the drum 12 extends inwardly beneath the wall 6, into abutment with the cross bar 8. There are upstanding ears 21 at the point of juncture between the back plate 18 and the flange 19. To the ears 21, a damper 22 is pivoted at 34. The damper 22 has upstanding projections 23. An operating member 24, in the form of a rod, is provided. The rod 24 slides in the opening 11. The inner end of the rod 24 is pivoted at 25 to the projections 23 on the damper 22. The space within the opening 3, to the right of the back plate 18 of the drum 12 in Figure 2 forms a fire place 35. A grate basket 32 extends outwardly from the lower part of the partition 1 and bounds the fire place 35. The throat 5 communicates with the fire place 35.

A pipe 26 extends upwardly along the part 6 of the partition 1. The upper end 27 of the pipe 26 communicates with the flue 2. The lower end 28 of the pipe 26 extends downwardly through the top 16 of the drum 12 and is prolonged horizontally, and broadened, within the drum 12. The end 28 of the pipe 26 communicates with a horizontally 90 elongated opening 29 in the back 18 of the drum 12. The part 18 also forms a back for the fire place 35. Air is admitted into the lower part of the drum 12 through an opening controlled by a damper 30 on the front 14 of the drum. The front 14 of the drum carries a removable water pan 31, adapted to secure a moistening of the air which is heated within the drum.

When a fire is built in the fire place 35, the room to the right of the partition 1 in Figure 2 will be warmed. The damper 22, under such circumstances, is moved, by the rod 24 to an open position, so that the products of combustion may pass upwardly from the fire place 35 through the flue 2. The draft, under such circumstances, is so direct that there is no appreciable draft to the pipe 26. It is unnecessary, therefore, to place a damper in any part of the pipe 26. If desired, the damper 22 may be swung over against the wall 7, into a closed position, as shown

in Figure 2. Then, the products of combustion will traverse the pipe 26 and be returned to the flue 2 through the upper end 27 of the pipe. The air within the drum 12 will be heated, and will be discharged into the room to the left of the partition 1, in Figure 2, through the perforations 17 in the top 16 of the drum 12, the air entering the drum under the control of the damper 30.

10 Having thus described the invention, what is claimed is:—

1. In a device of the class described, a partition having a flue, there being a transverse opening in the partition at the lower end of the flue, a drum mounted in one end of the opening and projecting outwardly beyond one side of the partition, means for admitting air into the lower portion of the drum, the drum including a top having an air outlet, a plate forming the back of the drum and forming the back of a fire place in the other end of the opening, the flue communicating with the fire place, a pipe communicating at its upper end with the flue, the lower end of the pipe being prolonged downwardly through the top of the drum and rearwardly within the drum, the lower end of the pipe communicating with the fire place, through the plate; a single damper controlling the passage of the products of

combustion from the fire place into the flue, and means for operating the damper.

2. In a device of the class described, a partition having a flue, there being a transverse opening in the partition at the lower end of the flue, a cross bar mounted in the lower portion of the partition, at the top of the opening, and supporting the upper portion of the partition, a drum in one end of the opening and projecting outwardly beyond one side of the partition, a plate forming the back of the drum and forming the back of a fire place in the other end of the opening, the flue communicating with the fire place, the plate comprising a substantially horizontal flange, means for securing said flange to the bar, a damper pivoted to the plate and controlling the passage of the products of combustion from the fire place into the flue, means for operating the damper, and a pipe communicating at its upper end with the flue, the pipe being extended downwardly into the drum and rearwardly within the drum, the lower end of the pipe communicating with the fire place, through the plate.

In testimony that I claim the foregoing as my own, I have hereto affixed my signature.

CAMERON ARTHUR KIDD.
